UNITED STATES PATENT OFFICE.

DE VER H. WARNER, OF BRIDGEPORT, CONNECTICUT, ASSIGNOR TO THE WARNER BROTHERS COMPANY, OF BRIDGEPORT, CONNECTICUT, A CORPORATION OF CONNECTICUT.

DESIGN FOR A HOSE-SUPPORTING LOOP.

56,042.

Specification for Design.

Patented Aug. 10, 1920.

Application filed January 13, 1920. Serial No. 351,266. Term of patent 14 years.

To all whom it may concern:

Be it known that I, DE VER H. WARNER, a citizen of the United States, and a resident of Bridgeport, in the county of Fairfield and State of Connecticut, have invented a new, original, and ornamental Design for Hose-Supporting Loops, of which the following is a specification, reference being had to the accompanying drawing, forming a part thereof.

Figure 1 is a rear view of a hose support-

ing loop showing my new design; and Fig. 2 is a front view thereof.

The distinguishing feature of my new design is the straight member A extending across and embracing the narrowed portions B of the sides of the loop.

I claim:

The ornamental design for a hose supporting loop as shown.

D. V. H. WARNER.
